EUGENE C. HERTEL, OF CHICAGO, ILLINOIS, ASSIGNOR TO SINCLAIR REFINING COMPANY, OF NEW YORK, N. Y., A CORPORATION OF MAINE.

ART OF CRACKING HYDROCARBON OILS.

Application filed January 12, 1928. Serial No. 246,262.

This invention relates to improvements in the cracking of higher boiling hydrocarbon oils, such as gas oil, for the production of lower boiling oils, such as gasoline or gasoline-line-containing oils, by distillation under superatmospheric pressure; more particularly the invention relates to improvements in such pressure distillation cracking operations in which higher boiling oil is circulated 5 through a heating zone, in which the oil is heated to a cracking temperature, to a vaporizing zone from which the vapors of the cracked oil including vapors of the desired lower boiling oil are taken off under super- 10 atmospheric pressure.

Pressure distillation cracking operations have been well known and widely practiced for many years; in one such known type of operation only oil free from unvaporized 20 components of oil which has passed through the heating zone is circulated therethrough, in another unvaporized oil is maintained in circulation through the heating zone. In one aspect, the present invention provides an improved 25 operation combining features of the two types of operations just mentioned, combined in a manner securing advantages of each and eliminating disadvantages of both.

Products of cracking operations usually 30 include, in addition to the desired lower boiling oils, pitch or pitch-like constituents which up to a certain point will dissolve in the oil being cracked but which when present in amounts exceeding the saturation limit 35 separate from the oil and, in externally heated apparatus, tend to deposit upon the surface through which heat is transferred to the oil where, due to the fact that such deposits conduct heat but poorly, overheating 40 results involving over-cracking of the oil being processed, further decomposition of such pitch or pitchlike constituents with the formation of coke or coky deposits which 45 can be removed only with difficulty and the imposition of unnecessarily severe strains upon the apparatus in which the operation is carried out.

As is described in Letters Patent No. 1,598,136 issued to the Sinclair Refining 50 Company, August 31, 1926, on an application of Eugene C. HerTEL, the concentration of such pitch or pitch-like constituents can be kept within the saturation limit by supplying raw oil to and discharging pitch-laden oil 55 from the operation at rates appropriately

regulated with respect to each other and with respect to the rate at which distillate is taken off. The oil components of pitch-laden oil discharged in such operation are usually suitable to be supplied to further cracking operations for the further recovery of the desired lower boiling oils, but it is usually necessary to separate the pitch or pitch-like constituents present before the oil is suitable for further cracking. 60

It will be apparent that, in general, the higher the concentration of pitch or pitch-like constituents in residual oil discharged from cracking operations the less burdensome is the separation of such pitch or pitch- 65 like constituents from the oil components. In one respect, the present invention provided an improved operation in which the concentration of pitch and pitch-like constituents in oil discharged from the cracking 70 operation may be made relatively high.

For certain purposes, particularly for use as motor fuels, gasoline or gasoline-like oils produced by the subjection of higher boiling oils to relatively severe cracking conditions, 75 particularly to relatively high cracking temperatures, are of special value; oils of high anti-knock value may thus be produced. The maintenance of such relatively more severe cracking conditions, however, usually 80 imposes additional stresses upon the apparatus in which the operation is carried out and, because continuance of the operation rapidly becomes either dangerous or impossible, frequently involves a substantial loss 85 in an increase in the proportion of time the apparatus is idle. In one aspect, the present invention provides an improved operation of special value and application in cases where the maintenance of such relatively more 90 severe cracking conditions is desirable or necessary.

According to the present invention, after an initial charge of oil is brought to cracking conditions of temperature and pressure, 100 higher boiling oil is circulated and recirculated from a vaporizing zone through a heating zone in which it is heated to a cracking temperature and back to the vaporizing zone, vapors of the cracked oil being taken off 105 from the vaporizing zone and raw oil being supplied to the higher boiling oil circulating through the heating zone as the operation continues, and, after a substantial amount of cracked oil has been taken off and before the 110

oil circulating through the heating zone becomes saturated with pitch, recirculation of unvaporized oil from the vaporizing zone through the heating zone is stopped, the circulation of raw oil through the heating zone being continued and vapors of the cracked oil being taken off from the vaporizing zone until a further substantial amount of cracked oil has been taken off. At the same time that the recirculation of unvaporized oil from the vaporizing zone through the heating zone is stopped, or somewhat later, the discharge of unvaporized oil from the vaporizing zone is begun, to prevent excessive accumulation of unvaporized oil in the vaporizing zone, but in carrying out this invention a relatively high concentration of pitch or pitch-like constituents in such discharged unvaporized oil may be maintained with advantage rather than with detriment to the operation as a whole. During the first period of operation in which vapors are taken off from the vaporizing zone, it is advantageous to recirculate the unvaporized oil from the vaporizing zone to the heating zone without discharging any of the unvaporized oil from the vaporizing zone. The vapors taken off from the vaporizing zone during both periods of operation are with advantage subjected to a refluxing operation from which higher boiling components in the vapors are recirculated as reflux condensate through the heating zone admixed with raw oil, the mixture also including during the first period of operation unvaporized oil recirculated from the vaporizing zone. The raw oil supplied to the operation is, with advantage, introduced directly into the vapors in such refluxing operation, thereby being preheated and at the same time cooling and condensing the vapors, the oil mixture from the refluxing operation in this case including unvaporized raw oil and reflux condensate. In terminating the operation it is advantageous to stop the discharge of unvaporized oil from the vaporizing zone and to resume the recirculation of such unvaporized oil through the heating zone while continuing to take off vapors of the cracked oil from the vaporizing zone for a further period.

The invention will be further described in connection with the accompanying drawings which illustrate, diagrammatically and conventionally, in elevation and partly in section with parts broken away, one form of apparatus adapted for carrying out the process of the invention, but it will be understood that this more detailed description is by way of illustration rather than limitation of the invention. While the process of the invention may be carried out in other and different forms of apparatus, the apparatus illustrated in the accompanying drawings has several special advantages; this particular apparatus is claimed in an application copending here-

with filed January 12, 1923, Serial No. 246,263.

Referring to the drawings, the pressure still system illustrated comprises a battery of heating tubes 2 arranged in the heating flue 70 of a furnace 3, a vaporizing drum 4, circulating connections 5, 6 and 7 including a pump 8 or other suitable forcing means 8, a valve 9 for closing the connection between the vaporizing drum 4 and the intake side of 75 the pump 8, a reflux tower 10 with suitable vapor connections 11 and reflux return connections 12 to the still proper, a connection 13 for introducing raw oil into the reflux tower 10, a condenser 14, a receiver 15, and a connection 16 for discharging unvaporized oil from the vaporizing drum 4. The distillate product is discharged from the receiver 15 through connection 17, and uncondensed vapors and gases through connection 18. 80 Pressure in the system is maintained and regulated by means of valve 19 in the vapor line 20 between the reflux tower 10 and the condenser 14, or by means of suitable valves arranged beyond the condenser or receiver. 85 Connection 21 is provided for initially charging the still at the beginning of a run and for pumping out the still at the end of a run. Connection 22 is provided for supplying cool oil, for example a portion of the raw 90 oil, to the bearings of the pump 8, or for introducing an additional amount of raw oil through such bearings. Connections 23, including suitable forcing means, are provided for recirculating over the heating tubes a 100 portion of the heating gases which have passed thereover, as described in Letters Patent No. 1,574,546 and No. 1,574,547 issued to the Sinclair Refining Company February 23, 1926, on application of John E. Bell. 105

The following example of an operation embodying the invention carried out for the production of gasoline from gas oil will illustrate the carrying out of the invention in the apparatus illustrated: The still is initially 110 charged with about 6,000-8,000 gallons of gas oil and, with the valve 9 open, pump 8 is started and the furnace 3 is fired. As soon as the pump 8 is started, raw oil is forced through connection 22 in through the bearings of the pump at the rate of about 250 gallons per hour. As the still charge is heated, any contained water or very light hydrocarbons are vaporized and permitted to escape through the vapor line 20. After a 120 period of about four to five hours, valve 10 is closed and the still is gradually brought to operating temperature and pressure, say in another four or five hours. When the pressure in the system reaches, for example, 125-150 lbs. per sq. in., the valve 19 is gradually opened and regulated to maintain the desired predetermined pressure in the system. At about the same time the introduction of raw oil through connection 13 into the upper 125 130

end of reflux tower 10 is begun and the rate of introduction regulated to maintain the desired temperature at the top of the reflux tower, for example 550° F. The rate at 5 which raw oil is introduced into the upper end of reflux tower 10 may reach 2,000 gallons per hour or more. Additional raw oil, for example to maintain the charge of oil in the vaporizing drum 4, may be supplied 10 through connection 22. The total rate at which raw oil is supplied may reach 2,500 gallons per hour or more. The vapors of the cracked oil escaping uncondensed from the reflux tower 10 through connection 20 15 are condensed in the condenser 14 from which the resulting condensate is discharged into receiver 15. During this first period of operation in which vapors are taken off from the operation, the charge of oil in the still 20 is circulated and recirculated through the heating tubes 2 from and to the vaporizing drum 4. Before the circulating still charge becomes saturated with pitch or pitch-like constituents, for example by the time the dis- 25 tillate taken off amounts to 15% or somewhat more of the total raw oil including the initial charge supplied to the operation, the valve 9 is gradually closed. This first period of operation after the still is brought to 30 operation conditions of temperature and pressure, may approximate two to three hours or longer. The closing of the valve 9 is done slowly to permit gradual self-adjustment of the operation to the change in oper- 35 ating conditions; for example complete closure of the valve 9 may require an hour. When the valve 9 is completely closed, but not until then, the discharge of unvaporized oil from the vaporizing drum 4 through con- 40 nection 16 is begun and regulated, for example, to maintain a constant level within the vaporizing drum. The discharge of unvaporized oil through connection 16 may be started immediately after the valve 9 is com- 45 pletely closed or particularly where there is a relatively small charge of oil in the vaporizing drum at the time, it may not be started until some time later, say an hour or longer. During the first period of operation, after the 50 still is brought to operating condition of temperature and pressure, the oil mixture circulated through the heating tubes 2 includes admixed reflux condensate and unvaporized raw oil from the reflux tower 10 and in addition unvaporized oil recirculated 55 through the heating tubes from the vaporizing drum 4. During the second period of operation, after the valve 9 is closed, the oil mixture circulating through the heating tubes 2 includes only admixed reflux condensate and unvaporized raw oil. In normal operation, the proportion of reflux condensate in the oil mixture circulated through the heating tubes during the second period 60 of operation several times exceeds that of raw oil. This second period of operation may last from 20 to 200 hours or longer, depending upon the particular stocks under treatment and the particular products desired. As the operation terminates, the fires are 70 first drawn and valve 9 is then gradually opened, over a period of from say one-half to one hour, while the introduction of raw oil through connection 13 is continued, as described above. At the same time, the rate 75 at which raw oil is supplied through connection 22, if in excess of about 250 gallons per hour, is reduced to that value. When the pressure in the system has dropped to say 80 60 lbs. per sq. in., or after a period of say 80 two hours, the introduction of raw oil is stopped and the pump 8 is stopped, the valve 19 is closed, and the still is pumped out through connection 21. After the still is 85 steamed out in the usual way it is then ready for cleaning. The valve 9 is with advantage kept closed during the cleaning operation.

In the foregoing example, pressures of 125-150 lbs. per sq. in. are given as an illustration of the pressures under which the operation may be carried out. It will be understood that higher or lower pressures, depending upon the particular stocks to be treated and the particular products desired, 90 may be used in carrying out the process of 95 the invention. In general it is advantageous to use higher pressures and correspondingly higher temperatures with more refractory stocks; with some stocks pressures as high as 300 lbs. per sq. in. or higher may be used. The cracking temperature to which the oil is subjected corresponds, with any particular stock, to the pressure under which the operation is carried out. The present invention is of special value and application in 100 connection with operations carried out under high pressure and at correspondingly high temperature in the treatment of relatively refractory stocks or in the maintenance of relatively severe cracking conditions.

The raw oil supplied to the operation in carrying out the process of the invention may be preheated, for example to a temperature in the neighborhood of 180-200° F. Raw oil 105 introduced into direct contact with vapors in a refluxing operation, as through connection 13 in the apparatus illustrated, should not be supplied at a temperature in excess of that making possible the maintenance of the desired temperature gradient under the prevailing pressure through the refluxing operation. The unvaporized oil discharged 110 from the vaporizing zone may be subjected to further treatment for the separation of oil components, to be returned to the cracking operation or subjected to some other cracking operation. For example, oil components of the discharged unvaporized oil 115 may be vaporized by reducing the pressure thereon as discharged and while still at high 120 125 130

temperature and the unvaporized residue then separated from vaporized oil components.

The vapors taken off from the vaporizing zone or from a subsequent refluxing operation may be subjected to direct fractionation for the recovery of a distillate product or products of desired boiling range eliminating any need for redistillation.

10 I claim:

1. In cracking hydrocarbon oils in operations in which higher boiling oil is circulated through a heating zone in which the oil is heated to a cracking temperature to a vaporizing zone from which vapors of the cracked oil are taken off under superatmospheric pressure, the improvement which comprises bringing an initial charge of oil to cracking conditions of temperature and pressure, then taking off vapors of the cracked oil from the vaporizing zone while circulating and recirculating higher boiling oil through the heating zone from and to the vaporizing zone and supplying raw oil to the oil circulating through the heating zone until a substantial amount of cracked oil has been taken off, and then, before the oil circulating through the heating zone becomes saturated with pitch, stopping the recirculation of unvaporized oil from the vaporizing zone through the heating zone while continuing to take off vapors of the cracked oil from the vaporizing zone and to circulate raw oil through the heating zone until a further substantial amount of cracked oil has been taken off.
2. In cracking hydrocarbon oils in operations in which higher boiling oil is circulated through a heating zone in which the oil is heated to a cracking temperature to a vaporizing zone from which vapors of the cracked oil are taken off under superatmospheric pressure, the improvement which comprises bringing an initial charge of oil to cracking conditions of temperature and pressure, then taking off vapors of the cracked oil from the vaporizing zone while circulating and recirculating higher boiling oil through the heating zone from and to the vaporizing zone and supplying raw oil to the oil circulating through the heating zone until a substantial amount of cracked oil has been taken off, and then, before the oil circulating through the heating zone becomes saturated with pitch, stopping the recirculation of unvaporized oil from the vaporizing zone through the heating zone while continuing to take off vapors of the cracked oil from the vaporizing zone and to circulate raw oil through the heating zone until a further substantial amount of cracked oil has been taken off.
3. In cracking hydrocarbon oils in operations in which higher boiling oil is circulated through a heating zone in which the oil is heated to a cracking temperature to a vaporizing zone from which vapors of the cracked oil are taken off under superatmospheric pressure, the improvement which comprises bringing an initial charge of oil to cracking conditions of temperature and pressure, then taking off vapors of the cracked oil from the vaporizing zone while circulating and recirculating higher boiling oil through the heating zone from and to the vaporizing zone and supplying raw oil to the oil circulating through the heating zone until a substantial amount of cracked oil has been taken off, and then, before the oil circulating through the heating zone becomes saturated with pitch, stopping the recirculation of unvaporized oil from the vaporizing zone through the heating zone while continuing to take off vapors of the cracked oil from the vaporizing zone and to circulate raw oil through the heating zone until a further substantial amount of cracked oil has been taken off.
4. In cracking hydrocarbon oils in operations in which higher boiling oil is circulated through a heating zone in which the oil is heated to a cracking temperature to a vaporizing zone from which vapors of the cracked oil are taken off under superatmospheric pressure, the improvement which comprises bringing an initial charge of oil to cracking conditions of temperature and pressure, then taking off vapors of the cracked oil from the vaporizing zone and subjecting them to a reflux operation in direct contact with raw oil introduced into the vapors in the refluxing operation while circulating admixed reflux condensate and unvaporized raw oil from the refluxing operation through the heating zone in admixture with unvaporized oil recirculated from the vaporizing zone until a substantial amount of cracked oil has been taken off, and then, before the oil circulating through the heating zone becomes saturated with pitch, stopping the recirculation of unvaporized oil from the vaporizing zone through the heating zone while continuing to subject vapors taken off from the vaporizing zone to the refluxing operation and to circulate admixed reflux condensate and unvaporized raw oil from the refluxing operation through the heating zone until a further substantial amount of cracked oil has been taken off, and, during the second mentioned period of operation in which vapors are taken off from the vaporizing zone, discharging unvaporized oil from the vaporizing zone.
5. In cracking hydrocarbon oils in operations in which higher boiling oil is circulated through a heating zone in which the oil is heated to a cracking temperature to a vaporizing zone from which vapors of the cracked oil are taken off under superatmospheric pressure, the improvement which comprises bringing an initial charge of oil to cracking conditions of temperature and pressure, then taking off vapors of the cracked oil from the vaporizing zone while circulating and recirculating higher boiling oil through the heating zone from and to the vaporizing zone without discharging unvaporized oil from the vaporizing zone and supplying raw oil to the oil circulating through the heating zone until a substantial amount of cracked oil has been taken off, and then, before the oil circulating through the heating zone becomes saturated with pitch, discharging unvaporized oil from the vaporizing zone and stopping the recirculation of unvaporized oil from the vaporizing zone through the heating zone while continuing to take off vapors of the cracked oil from the vaporizing zone and to circulate raw oil through the heating zone until a further substantial amount of cracked oil has been taken off.

zone from which vapors of the cracked oil are taken off under superatmospheric pressure, the improvement which comprises bringing an initial charge of oil to cracking conditions 5 of temperature and pressure, then taking off vapors of the cracked oil from the vaporizing zone while circulating and recirculating higher boiling oil through the heating zone from and to the vaporizing zone and supplying raw 10 oil to the oil circulating through the heating zone until a substantial amount of cracked oil has been taken off, and then, before the oil circulating through the heating zone becomes saturated with pitch, stopping the recirculation 15 of unvaporized oil from the vaporizing zone through the heating zone while continuing the take off vapors of the cracked oil from the vaporizing zone and circulating raw oil admixed with higher boiling components condensed 20 from the vapors taken off from the vaporizing zone through the heating zone until a further substantial amount of cracked oil has been taken off, and, during the second mentioned period of operation in which 25 vapors are taken off from the vaporizing zone, discharging unvaporized oil from the vaporizing zone.

6. In cracking hydrocarbon oils in operations in which higher boiling oil is circulated 30 through a heating zone in which the oil is heated to a cracking temperature to a vaporizing zone from which vapors of the cracked oil

are taken off under superatmospheric pressure, the improvement which comprises bringing an initial charge of oil to cracking conditions of temperature and pressure, then taking off vapors of the cracked oil from the vaporizing zone while circulating and recirculating higher boiling oil through the heating zone from and to the vaporizing zone and 35 supplying raw oil to the oil circulating through the heating zone until a substantial amount of cracked oil has been taken off, and then, before the oil circulating through the heating zone becomes saturated with pitch, 40 stopping the recirculation of unvaporized oil from the vaporizing zone through the heating zone and discharging unvaporized oil from the vaporizing zone while continuing to take off vapors of the cracked oil from the 45 vaporizing zone and to circulate raw oil through the heating zone until a further substantial amount of cracked oil has been taken off, and terminating the operation by stopping the discharge of unvaporized oil from 50 the vaporizing zone and resuming the recirculation of unvaporized oil therefrom through the heating zone while continuing to take off vapors of the cracked oil from the 55 vaporizing zone.

In testimony whereof, I have subscribed my name. 60

EUGENE C. HERTHEL.
